UNITED STATES PATENT OFFICE.

SEYMOUR FERGUSON, OF OCOTLAN, MEXICO.

ROCK-DRILL.

1,214,661.

Specification of Letters Patent.

Patented Feb. 6, 1917.

Application filed June 30, 1911, Serial No. 838,199. Renewed December 26, 1916. Serial No. 139,047.

To all whom it may concern:

Be it known that I, SEYMOUR FERGUSON, a citizen of the United States of America, residing at the city of Ocotlan, in the State 5 of Oaxaca, Mexico, have invented certain new and useful Improvements in Rock-Drills, of which the following is a description.

My invention relates to rock drills and 10 consists briefly of an improved body mechanism capable of receiving interchangeable attachments for adapting it to different purposes; thus it may form a part of a drill of the hammer type, or a drill of the piston 15 or cylinder type, or a machine for doing other work in which blows are delivered rapidly in succession, for example, riveting.

My invention also comprises various details of construction having for their object 20 the increasing of the durability and efficiency of the said mechanism and the ease with which the parts may be disassembled for repairs; and for their further object the elimination of unnecessary wear, vibration, 25 friction, recoil and air leakage.

In order that the invention may be more fully understood, reference is hereby made to the accompanying drawings, wherein—

Figure I is a side view taken on the line 30 I—I, Fig. IX and showing my invention embodied in a drill of the hammer type; Fig. II is a central, vertical, longitudinal section of the same; Fig. III is a central, vertical, longitudinal section of an interchangeable attachment adapted to be applied to the body portion of the drill of Figs. I and II; Fig. IV is a perspective of the hammer head; Fig. V is a perspective of the rotatable cylinder containing the 35 hammer head; Fig. VI is an enlarged section on line VI—VI, Fig. II, with parts cut away; Fig. VII is an enlarged section on line VII—VII, Fig. II; Fig. VIII is an 40 enlarged section on line VIII—VIII, Fig. III; Fig. IX is an enlarged section on line IX—IX, Fig. II, showing the operating mechanism; and Fig. X is an enlarged section on line X—X of Fig. I.

Similar reference numerals refer to similar parts throughout the drawings.

The casing of the body mechanism, hereinafter referred to as the main casing preferably consists of a seamless integral cylinder 1, the rear end of which is fitted with a removable back head 2. Lateral extensions 6 are formed integral with the cylinder

and provide rectangular seats for a pair of removable sections 69 and 69' secured in place by bolts 68 passing through said extensions. Journal boxes or bushings 8 are 60 mounted in said sections and a crank shaft 5 is journaled therein. The back head 2 is secured in position in any desired manner as by cap screws 94 passing therethrough and threaded in the sections 69 and 69' respectively. The lateral extensions 6 open rearwardly as shown and permit the ready removal from the cylinder 1 in a direction which is rearward and parallel to its axis, of the sections 69 and 69', together with the 70 journals carried thereby, the crank shaft 5 and all parts connected to and operated thereby. These parts may be removed from the cylinder by merely removing the bolts 68. By this construction, repairs and renewals of worn parts are facilitated, and since a one-piece or seamless cylinder is used, unnecessary leakage of air from the interior is avoided. The cylinder 1, sections 69 and 69', and back head 2 are closely 80 fitted together, as shown, to form a dust-proof casing.

Upon the center or throw of the crank shaft 5 is mounted a sliding journal box 7, which slides up and down in a cross head 4. 85 This cross head is adapted to reciprocate longitudinally in casing 1, being guided therein by longitudinal grooves 56 provided for that purpose, which, in the embodiment shown, are at the top and bottom of the 90 casing. The operation of a device of this kind causes an excessive amount of wear between the journal box 7 and its bearing surface in the cross head 4 which it has not seemed possible to obviate heretofore in a 95 satisfactory manner. I have devised a simple attachment which does not interfere with the operation of any part of the mechanism, consisting of a rectangular plate 3, arranged in the cross head in contact with 100 journal box 7, and which can be adjusted to take up wear by means of liners and a bolt 49.

The front of the cross head 4 is provided with a circular recess containing a cup-shaped member 9, which is adapted to fit over a portion 12 for a purpose to be hereinafter described. At the center of said circular recess in the cross head 4, a piston rod 10 is secured in any suitable manner, as 110 by a screw thread connection, said piston rod by its connection also serving to secure

in place said cup-shaped member 9. At the front end of said piston rod 10 is a hollow piston 15 with its open end provided with a ring 20, in the center of which is journaled 5 a shaft 17'. The front portion of said shaft, beyond said disk is provided with spiral grooves 23; and upon the rear end is mounted a toothed ratchet wheel 17 fitting within the hollow piston 15. Mounted on 10 the interior of the hollow piston and adapted to engage in the teeth of the ratchet wheel 17 are pawls 21.

Piston 15 is mounted within and fitted to form a pneumatic cushion connection with 15 a driver or tool actuating cylinder or plunger 12-14, a portion of which has a sliding and rotatable fit within the interior of the casing 1. The rear portion 12 of said driver cylinder is of the same diameter as 20 the interior of the cup-shaped member 9, so that an air cushion is formed between the two, as will be described later. The piston rod 10 extends through an opening provided therefor in the rear end of said portion 12, 25 the passage being made air-tight by a suitable stuffing box 13. The front portion 14 of said driver cylinder is formed with an extension 14' reduced in size and bored from the rear to receive a tube 22, secured therein 30 in any suitable manner as by screw thread connection. Said tube 22 is provided with interior spiral ribs 24 adapted to engage the spiral grooves 23 of the front portion of the shaft 17'.

35 The operating mechanism for crank shaft 5 is illustrated by Fig. IX of the drawings, wherein removable section 69 is shown with an out-turned annular flange. Over said section is fitted a horizontally flanged ring 40 70, provided on the outer surface of said horizontal flange with screw threads. A circular gear housing 72 is attached to said ring 70 by means of an internally threaded, circular, horizontal extension on said housing, adapted to screw on the threaded horizontal flange of said ring. Openings in 45 said gear housing have screwed therein cups 73, between which and the cone bearing 74 secured to a shaft 76, are rollers 75. The 50 recesses in the cups 73 and bearing 74 are located at such an angle with respect to the side of the housing 72 and to the shaft 76, that by screwing said cups 73 slightly inward, the recesses are made smaller in diameter, thereby taking up any wear which may occur. This adjustment is convenient, simple, and does not interfere in any way with the operation of a mechanism of this character. The ends of shaft 76 are provided with 55 screw threads, on one of which is screwed a retaining cap 78, and on the other of which is screwed a retaining cap 77, the latter having a longitudinal, circular extension provided with external screw threads so that 60 the driving mechanism may be attached 65

readily to any suitable source of power. This simple means of connection is a distinct advantage in a machine of this kind, which necessarily often is moved from place to place. On said shaft 76 is secured also a 70 bevel gear 79, adapted to mesh with a bevel gear 71 secured in any suitable manner, as by screw threads, to an end of the crank shaft 5.

The operation of the mechanism thus far 75 described is as follows:—When power is applied to the cap 77, shaft 76 is revolved, which revolution is imparted to the crank shaft 5 through gears 79 and 71. The rotation of said crank shaft causes the cross head 80 4 and the attached piston rod 10 and piston 15 to reciprocate. The forward movement of said piston 15 compresses the air between its ring 20 and the front wall 87 of the portion 14 until the compression is sufficient 85 to cause the driver cylinder 12-14 to move forward with the continued forward movement of the piston 15. During this forward movement of the piston 15, the spirally grooved forward extension of the shaft 17' 90 enters the tube 22, and since said grooves are engaged by the ribs 24 on said tube, the shaft 17' rotates in the direction of the arrow shown in Fig. VI of the drawings, since the teeth of the ratchet 17 on said shaft and the pawls 21 on the interior of the piston 15, are so arranged that they are inoperative 95 during this forward movement, and their friction is less than that of the parts of the mechanism connected to the driver cylinder 12-14. On the rear movement of the piston 15, however, the pawls 21 operatively engage the teeth of the ratchet 17. As before described, said pawls 21 are mounted on the interior of the piston 15, and as said piston cannot turn, owing to its connection by the piston rod 10 with the non-rotatable cross head 4, the ratchet 17 is held firmly from rotation. The withdrawal then, 100 of the now non-rotatable spiral grooved extension of the shaft 17' from the spirally ribbed interior of the tube 22, causes the entire driver cylinder 12-14 to rotate, together with the parts attached thereto as 105 will be hereinafter described.

To improve the general operation and to 110 increase the efficiency of a drive of this type, a system of air regulation has been provided, comprising in-take ports 18 in the driver cylinder 12-14; and an air passage 11 through the piston rod 10, ratchet 17, and shaft 17', said air passage being provided in the piston 15 and ratchet 17, with a spring-pressed valve 16 opening in the direction of the arrow shown in said air passage in Fig. 1120 II of the drawings. The in-take ports 18 are so arranged in reference to the piston 15 that the latter acts as a valve to close a port and thereby compress the air against the piston's advance, and to uncover a port behind it 115 125 130

to destroy any vacuum. The opening of the air passage 11 at the rear end of the piston rod 10, is so arranged that said opening will be closed by the driver cylinder 12—14 when near the end of its rearward stroke, the portion 12 and the cup-shaped member 9 fitting so nicely that an air cushion is formed, thereby preventing knocking between the end of portion 12 and the back wall of said member 9. Another air cushion is formed between the rear face of the piston and the member 12. By this arrangement a double cushioning effect is obtained and any danger of the respective heads hitting together is entirely obviated. The air forced through air passage 11 through the valve 16 during the main portion of the rearward stroke, passes to the space between retreating ring 20 and the front wall 87 of the portion 14, so that a full supply of air is there present, thereby assisting the action of the front port 18 to destroy any vacuum, and insuring sufficient air to form a cushion between the piston and member 14 on the forward stroke. In connection with the maintenance of an air cushion between the piston and the ends of the driver cylinder 12—14, the manner of securing together the two portions thereof is an important feature of my invention. This driver cylinder cannot be made integral, as the piston 15 and its allied parts must be placed therein, and a joint is likely to develop air leakage due to heating and unequal expansion of the parts during the operation of the machine. I have so located the connection of the portions 12 and 14 with reference to the cylinder, therefore, that any leakage in said connection will not affect the compression at either end, the result being that the piston practically has an integral cylinder in which to effect its compression function.

At the front of the casing 1 is a water attachment injector 41 which consists of an enlarged portion having an inlet end 48 adapted to be connected with any source of water supply and an oppositely placed outlet end adapted to be connected to the water inlet in the extension casing 55. In the enlarged portion is a nozzle 46 pointing toward the outlet end and connected with the interior of the casing 1 by a valve 42, forced against its valve seat 43 by a spring 44. The forward movement of the driver cylinder 12—14 forces the air through the nozzle 46, thereby creating a vacuum behind the same in the enlarged portion and drawing forward the water, where it mixes with the air and is forced through the outlet. An inlet port 95 (Fig. I) controlled by a check valve (not shown) is provided inside of the casing 1 to insure a constant supply of air for this purpose.

An important feature of my invention is the adaptability of the foregoing described

drill proper to be used with different types of attachments embodying different methods of operation without any change in said drill proper. Two preferred embodiments of such types of attachment, both of which comprises novel features, are shown in the drawings, one of which is attached to the drill proper as disclosed in Fig. II, and the other of which is shown separately, as disclosed in Fig. III.

The attachment shown in Fig. II is of the so-called hammer type, the drill being pressed against the rock or other substance to be operated upon and hammered by a suitable portion of the mechanism, much after the manner in which an artisan would be an ordinary hand drill and hammer. The numeral 55 indicates the casing of the attachment, which preferably consists of an integral cylinder or extension casing adapted to be attached readily to the main casing 1 of the body mechanism, as by screw threads as shown at "A". Rotatably mounted in the interior of said casing 55 is a long cylindrical body or sleeve 29 (Fig. V), having interior longitudinal grooves 28, and held in position by abutting shoulders as designated at "X" and by a cap 38 which screws on the outer end of the casing 55. Attached firmly to the front end of extension 14' of the driver cylinder 12—14, as by screw thread attachment, is a hammer head 26, adapted to slide within the cylindrical body 29 and having ribs 27 to engage the grooves 28 in said cylindrical body.

A chuck 30 is fixed within the outer end of cylindrical body 29, as by screw threads, abutting shoulders "Y" fixing their relative positions. Within the chuck 30 is slidably mounted a buffer block 34, which receives the impact of the hammer head 26 on its rear end, and supports the drill 40 in a socket provided for that purpose in its front end. An annular shoulder is formed on chuck 30 and a corresponding shoulder 110 formed on the buffer block 34 to inclose a spiral spring 35, which is compressed when the drill is pressed against the substance to be operated upon, thereby maintaining the drill 40 in close contact with the buffer block 34. A nose bushing 36 at the front of the chuck 30, serves to support the drill 40 and maintain it in alignment. To permit the insertion of said nose bushing and other details of construction to be described later, the chuck 30 preferably is formed in two parts secured together by dowel pins 64 as shown in Fig. VII. The drill 40 is held in place by a rectangular key 37 which passes through suitable openings in the chuck 30 115 and nose bushing 36, and engages a longitudinal, rectangular, side recess 39 provided for that purpose in the shank of the drill 40. Said rectangular key is maintained in operative position (Fig. VII) by spring- 120

pressed bolt 65 secured in place by screw cap 66, said bolt being adapted to enter notches 67 in the side of the key. The lower part of said key is cut away to provide for the withdrawal of the tool 40 when the key is raised, as will be evident from an inspection of said Fig. VII. It will be evident that the forward movement of the driver cylinder 12-14 will drive the hammer head 26 against the buffer block 34, thereby giving the drill 40 its operating impetus. Upon the rearward movement of the driver cylinder 12-14 and attached hammer head 26 with their consequent rotation as above described, the cylindrical body 29 will be rotated by the engagement of its grooves with the ribs of the hammer head 26. The rotation of the said body 29 rotates the chuck 30 fixed thereto, which causes the rotation of the drill 40 through their key and recess connection, so that on the next forward impetus the cutting edges of the drill will not strike in exactly the same place. It will be noted that the engagement of said key 37 with the tool 40 is such, that while they rotate together, the tool has longitudinal movement independently thereof owing to the length of its side recess 39, so that the energy of the hammer blow is unimpaired. The water attachment 41 is connected to the water inlet of the casing 55 by a pipe 45 and elbow 47, the water being forced from the outlet of said water attachment through said inlet, thence through water passages 31 provided for that purpose in cylindrical body 29, buffer block 34, and drill 40, to the front of the drill to wash away chips of stone and keep the parts cool. Suitable packing 32 is provided at necessary points to prevent water leakage.

The attachment shown in Fig. III is of the so-called piston type, whereby the drill is connected directly to the driver cylinder 12-14 and reciprocates therewith. The casing of this attachment is indicated by the numeral 57 within which is a piston 58, having its front end cored out to receive a bushing 63 in which the drill 40 is inserted. A novel locking device for the drill is shown on this attachment (Figs. III and VIII) comprising a block 60 adapted to pass through suitable recesses provided therefor in the piston 58 and the bushing 63 into engagement with a recess in the shank of tool 40. Said block 60 is pressed outwardly by springs 62, and is forced and held in operative position by a locking device 59, comprising a prismatical clamp having its base rounding and off center, and adapted to fit in a semi-circular recess provided therefor in the bottom of the chuck 58. The eccentric shape of said base is so designed that when the top of the prismatical clamp 59 is forced to the left, (Fig. III) a cam action 65 is secured which forces block 60 more and

more tightly against the drill 40. It will be evident that the impact of the drill 40 against this clamp will cause the locking device to tighten, thereby preventing accidental displacement of said drill. A slight tap is sufficient to loosen the clamp when it is desired to remove the drill 40. The block 60 then is pressed down until the top of the clamp 59 will pass over shoulder 61 on said block 60, whereby the entire locking device 59 may be removed from the cylinder.

The external surface of the rear of the casing 57 is provided with screw threads, the same in all respects as those on the casing 55 of the hammer type shown in Fig. II. The rear end of the cylinder 58 likewise is provided with screw threads the same in all respects as those on the hammer head 26 of the hammer type shown in Fig. II. It is only necessary, therefore, to unscrew the casing and hammer head of the hammer type attachment and substitute therefor the casing and piston of the piston type attachment to utilize the mechanism of the drill proper for the piston type of drill. Said piston type likewise is provided with means adapted to utilize the water attachment 41, consisting of an elbow 47 to be connected to said attachment 41, (which necessarily has the pipe 45 removed therefrom when the hammer type of attachment is removed), and water passages 31 and 96 leading to the end of the drill 40. Suitable packing 32 is provided at necessary points to prevent water leakage.

The reference numeral 80 indicates a support for the drill casing 1 and whatever type of attachment may be attached thereto, on which the drill as a whole can be longitudinally adjusted to advance the tool to and from operative position. Said support is mounted on a base 81, adapted to be mounted pivotally upon a suitable pedestal or tripod not shown. The support 80 is provided upon its upper face with guides 88 designed to receive complementary inclined guides 89 formed on the lower portion of the casing. Said support 80 also is provided with an offset 90 adapted to be engaged by guiding blocks 82, bolted or otherwise secured to the casing, thereby preventing any upward movement of the drill relative to its support. Formed integrally with said casing is an extension 50 having a longitudinally disposed bore 91, in which is mounted bushings 51-52, having outwardly turned flanges at the ends thereof. The flange of bushing 52 is formed with a flat upper face adapted to rest against a similarly formed flat face on the under part of drill casing 1, thereby holding said bushing from rotation. The flange of bushing 51 is provided with a plurality of peripherally arranged notches "a" adapted to register with one of a plurality of corresponding

notches "b" formed on the under face of casing 1, said notches being adapted to receive a pin 54 when a pair of notches is brought in registration. The pin 54 is held in place by a lug projecting from the lower edge of back head 2. The bushings 51 and 52 are internally threaded to receive a feed screw 53, its forward end being journaled in a thrust block 92 carried by the forward end 10 of support 80, and its rear end being provided with an integral collar 93 which acts as a stop to limit the rearward movement of casing 1 and with a handle 83 to operate said screw. By turning the handle 83, the 15 drill as a whole can be advanced or retracted within the limits of said feed screw mechanism.

Many modifications will be apparent to those skilled in the art, my invention not 20 being limited to the particular embodiment described, but consisting broadly of a mechanism adapted to cooperate with attachments of various types, together with improvements in the entire combination and in 25 the several constituent parts thereof.

Having thus disclosed one embodiment of my invention, what I claim and desire to protect by Letters Patent is:

1. The combination with a casing, of a reciprocating cross head, a driver cylinder 30 closed at both ends, and a piston within said cylinder and attached to said cross head, said cross head being provided with a cup adapted to closely receive a portion of said driver cylinder therein and form a cushion of compressed air between the two, substantially as set forth.

2. The combination with a casing, of a reciprocating cross head, a cup-shaped member 40 removably inserted in the forward end thereof, a cylinder closed at both ends and having a portion closely receivable into said cup-shaped member, a piston in said cylinder, and a piston rod connected thereto and 45 engaged in said cross head to secure the cup-shaped member in place, substantially as set forth.

3. The combination with a casing, of means therein comprising a cylinder closed 50 at both ends and having intake ports, a piston in said cylinder, a piston rod having an air passage connecting the space in advance of the piston with the space in the rear of the cylinder, a valve controlling said passage, and means for receiving the rear end of the cylinder during the reciprocation of the piston to form an air cushion and to discharge air through said air passage, substantially as set forth.

4. The combination with a casing, of a reciprocating cross head, a driver cylinder 60 closed at both ends, and a piston within said cylinder and attached to said cross head by its piston rod, said cross head being provided with a cup adapted to closely

receive a portion of said driver cylinder therein to form an air cushion between the two, and said piston and its rod being provided with an air passage having a port and a valve therein, through which air is forced 70 from said cushioning cup into the chamber in front of said piston, substantially as set forth.

5. The combination with a casing, of a reciprocating cross head, a driver cylinder 75 closed at both ends, and a piston within said cylinder and attached to said cross head by its piston rod, said cross head being provided with a cup adapted to closely receive a portion of said driver cylinder therein to 80 form an air cushion between the two, and said piston and its rod being provided with an air passage having a port and the inlet of said air passage being so placed as to be closed by said cylinder before said cylinder 85 reaches the end of its rearward stroke, substantially as set forth.

6. The combination with a casing, of a reciprocating cross head having a cup at its forward end, a sectional cylinder, one portion 90 of which is adapted to closely fit within the forward end of the cross head, said cylinder being closed at both ends and having intake ports, a piston movable in said cylinder and controlling said ports, a piston 95 rod connected with the cross head and having a longitudinal air passage opening at one end into the cup at the forward end of the cross head, and a valve controlling said passage, substantially as set forth. 100

7. The combination with a casing, of a cross head therein, a cup in the forward end of the cross head, a cylinder within the casing, said cylinder being closed at both ends and having one portion adapted to be closely 105 received within the cup portion of the cross head, a piston rod connected with the cross head, a piston carried by the piston rod within the cylinder, said piston being hollow, a ratchet wheel within the piston and 110 having a forwardly extending shaft with spiral grooves, a cooperating member in the forward end of the cylinder engageable with said grooves for rotating said shaft, and a valved air passage extending through 115 the piston rod and piston and connecting said cup with the chamber in front of the piston, substantially as set forth.

8. The combination of a casing, an actuating member therein, a cylinder closed at 120 both ends and a piston therein, one of said last named members being connected to said actuating member and driving the other by air compression, said cylinder being composed of two cup-shaped portions secured 125 together, the union being adjacent the center of the cylinder whereby leakage of air at said union is avoided, substantially as set forth.

9. The combination with a casing, of a 130

- 6
- cylinder therein constructed of two cup-shaped portions secured together end to end, and a piston operating within said cylinder to drive said cylinder by air compression, whereby any leakage of air in the joint of said portions will not affect the air compression formed in said cup shaped portions, substantially as set forth. 5
10. The combination with a casing, of a cylinder, therein constructed of two cup shaped portions having recesses of substantial volume and secured together end to end, a piston within said cylinder operating in said recesses, whereby air compression 15 formed in said recesses is unaffected by leakage of air in the joint between said portions, said portions being formed with intake ports upon opposite sides of the joint between such portions, substantially as set forth. 20
11. The combination with a main casing having a forward open end, of driving means therein comprising a reciprocating member, a plunger having a cushion connection therewith, and an extension casing removably secured to said forward end of said main casing, the forward end of said plunger being situated within the body formed by the main and extension casings 25 and provided with means for removably securing thereto interchangeable attachments, substantially as set forth. 30
12. The combination with a main casing having a forward open end provided with means for removable attachment of an extension casing, of driving means therein comprising a reciprocating member and a plunger having a cushion connection therewith, the forward end of said plunger being provided with means for removably securing thereto interchangeable attachments, an extension casing and drill holding means in said extension casing in alinement with said plunger, substantially as set forth. 35
- 40
13. The combination with a main casing, of a plunger therein, means for actuating said plunger, an extension casing on the main casing, said extension casing being removable, drill holding means carried by said extension casing, and means permitting interchangeable connection of attachments of different types to said plunger, substantially as set forth. 45
14. The combination with a main casing, of means therein comprising a cylinder, a piston within the cylinder, an extension casing, means therein for carrying a drill, said extension casing being removably connected with said main casing, and the forward end of said cylinder having means for removably securing interchangeable attachments, substantially as set forth. 55
15. A main casing, an extension casing having a rear open end and means for removably uniting the same to the main cas- 60
- ing, a cylinder having closed ends, a portion of said cylinder being movable within the main casing and a portion including the forward end thereof being movable within the extension casing and having means for removably securing interchangeable attachments, a piston having a cushion connection with said cylinder, and means for actuating said piston, substantially as set forth. 70
16. The combination of a seamless cylinder, a piston mounted therein, means comprising a transverse drive shaft for operating said piston, a removable back head closing the rear end of said cylinder and bearings carried by said back head, said drive shaft being mounted in said bearings, substantially as set forth. 75
17. In a drill, the combination of a cylindrical casing, a cylinder fitted to the bore thereof and having ends, a piston fitted to the bore of said cylinder, means for operating one of said last named members, an injector, an outlet from said casing so arranged that said cylinder causes the discharge of air from the interior of the casing into said injector, tool holding means, and a conduit for conducting fluid discharged from the injector into the tool holding means, substantially as set forth. 80
18. In a drill, a cylindrical casing, a cylinder fitted within the bore thereof and free to reciprocate therein, an injector communicating with the bore of said casing, said cylinder having ends and acting as a plunger to pump air or other fluid from the bore of said casing into said injector, a piston within said cylinder, means for operating said piston, tool holding means, and a conduit for conducting fluid discharged from the injector into the tool holding means, substantially as set forth. 85
19. In a drill, a cylindrical casing, a cylinder fitted within the bore thereof and free to reciprocate therein, an injector communicating with the bore of said casing, said cylinder having ends and acting as a plunger to pump air or other fluid from the bore of said casing into said injector, a piston within said cylinder, means for operating said piston, and drill holding means carried by said casing, and having a water passage therethrough, said passage communicating with the bore of said casing through said injector, substantially as set forth. 90
20. In a drill, a cylindrical casing having an air outlet, an injector having a water inlet and an air nozzle fed from said air outlet, a tool actuating plunger in said casing, reciprocating means for actuating said plunger, means for driving said actuating means, the movement of said plunger causing air to be forced through said outlet, tool holding means, and a conduit for conducting fluid discharged from the injector into the tool holding means, substantially as set forth. 100
- 110
- 115
- 120
- 125
- 130

21. In a drill, a casing, drill holding means having a water passage therethrough, an injector connected with said passage and having a water inlet and an air nozzle, said nozzle communicating with the interior of said casing, and a plunger for forcing air through said nozzle and actuating the drill tool, substantially as set forth.
22. In a drill, a casing, drill holding means having a water passage therethrough, an injector connected with said passage and having a water inlet and an air nozzle, said nozzle being fed from the interior of said casing, and unitary means for simultaneously forcing air through said nozzle and delivering a blow upon said drill holding means, substantially as set forth.
23. In a drill, the combination of a main casing, a tool actuating plunger therein, a removable extension casing secured to said main casing and containing drill holding means having a water passage therethrough, and a water attachment on said main casing operated by air forced therethrough by the action of said plunger to force water into the passage in said drill holding means, substantially as set forth.
24. In a drill, the combination with a casing, of a tool actuating plunger therein, drill holding means having a water passage therethrough, and a water injector operated by air forced therethrough by the action of said plunger to force water through the passage in said drill holding means, substantially as set forth.
25. In a drill, the combination with a main casing, of a tool actuating plunger therein, means for actuating the same, a removable extension casing on the main casing, an injector for connection with a water supply, and a connection from the interior of the main casing to the extension casing through said injector, the movement of said plunger causing water to be injected into said extension casing by air from the main casing, substantially as set forth.
26. In a drill, the combination with a main casing having a forward open end provided with means for removable attachment of an extension casing, of driving means therein comprising a reciprocating member and a plunger having a cushion connection therewith, the forward end of said plunger being provided with means for removably securing thereto interchangeable attachments, and an injector having a nozzle communicating with the interior of said main casing and supplied with air therefrom by the action of said plunger, and a forward open end provided with means for removably securing thereto interchangeable attachments, substantially as set forth.
27. In a drill, the combination with a main casing having a forward open end provided with means for removable attachment of an extension casing, of tool actuating means therein comprising a reciprocating plunger, an extension casing attached to said main casing, drill holding means in said extension casing adapted to be operated by said plunger and having a water passage therein, and a water attachment on said main casing connected to said water passage and actuated by air forced out of said main casing by said plunger, substantially as set forth.

This specification signed and witnessed this 10th day of June 1911.
